UNITED STATES PATENT OFFICE.

COLLIN THOMPSON, OF OKOLONA, MISSISSIPPI.

RAILROAD TIE AND RAIL FASTENER.

Application filed October 12, 1923. Serial No. 668,247.

To all whom it may concern:

Be it known that I, COLLIN THOMPSON, citizen of the United States, residing at Okolona, in the county of Chickasaw and State of Mississippi, have invented certain new and useful Improvements in Railroad Ties and Rail Fasteners, of which the following is a specification.

This invention relates to railroad tie and rail fasteners therefor, and has particular reference to a device of this kind embodying a rail seat formed of a block of metallic material embedded in the upper surface of a concrete or other molded tie.

The primary object of the invention is to provide a construction of the above kind, which embraces the desired qualities of simplicity, durability, and efficiency in operation.

Another object of the invention is to provide a rail seat block for composition railway ties having simple and efficient means for securing a rail thereon.

A further object is to provide rail fastening means capable of being easily and expeditiously adjusted to its operative position for holding a rail in place.

Other objects will appear as the nature of the invention is better understood, and the same consists in the novel form, combination, and arrangement of parts hereinafter more fully described, shown in the accompanying drawings, and claimed.

In the drawings, wherein like reference characters indicate corresponding parts throughout the several views:

Figure 1 is a fragmentary side elevation view illustrating a railroad tie, constructed in accordance with the present invention, and embodying a metallic rail seat block having rail fastening devices constructed in accordance with the present invention.

Figure 2 is a top plan view of the device shown in Figure 1.

Figure 3 is a fragmentary vertical transverse sectional view, taken substantially upon the line 3—3 of Figure 1.

Figure 4 is a fragmentary horizontal sectional view, taken on the line 4—4 of Figure 1.

Figure 5 is an enlarged perspective view of one of the rail engaging elements, and

Figure 6 is a view similar to Figure 5 of one of the wedges for operating the rail engaging element.

Referring more in detail to the drawings,

5 indicates a railroad tie that is moulded from any suitable composition such as concrete, with a rail seat forming block 6 embedded, preferably by molding in, in the upper surface of each end portion thereof during the moulding thereof, so that the upper surface of each block is flush with the upper surface of the tie as shown clearly in Figure 1. The block 6 is of general trapezoidal form in side elevation and has its sides flush with the sides of the tie as shown in Figure 2, suitable central ribs 7 being provided upon the inclined ends of the seat block 6, whereby sidewise displacement of the same from the tie is prevented under ordinary conditions.

The seat block 6 is provided with a pair of vertical openings 8 in which are slidably positioned the vertically movable rail engaging elements 9, said elements being in the form of elongated bars having inturned lips 10 upon the upper ends thereof to engage over the opposite base flanges of the rail 11 that is disposed upon the upper surface of the block 6 and extends transversely of the latter. As shown in Figure 2, the vertical openings 8 are provided in the block 6 in such manner as to position the rail engaging elements 9 at diagonally related points with respect to the longitudinal axis of the rail 11, said rail engaging elements being thereby respectively located closer to one side of the block 6 than to the other whereby staggered contact is had with the base flanges of the rail.

The block 6 is provided with a pair of horizontal transverse openings 12, each of which intersects one of the vertical openings 8, and slidably in the transverse openings 12 are wedge elements 13 that are movable transversely of the tie and in tapered notches 14 provided in the inner edges of the rail engaging element 9.

It is thus apparent that when the base flanges of the rail 11 are engaged under the lips 10 of the rail engaging elements 9, the latter will be drawn downwardly to tightly fasten the rail upon the upper surface of the block 6 when the wedges 13 are shifted transversely of the tie in one direction. For causing this shifting of the wedges 13, the latter are provided with screw threaded stems 15 upon one end with respect to each of the same, and nuts 16 are threaded upon these stems in position to bear against washers 17 disposed on the stems 15 and against

the adjacent side of the block 6. A second nut 18 may be threaded upon each of the stems for locking the adjusting nuts 16 against shutting off of the stems 15 after they have been tightly adjusted. It is also apparent that upon backing the nuts 18 and 16 off of the stems 15 for a sufficient distance, the rail engaging element 9 will be loosened sufficiently to permit shifting of the rail 11 relative to the tie. By completely removing the nuts, the wedges may be removed for permitting removal of the rail engaging elements 9, whereby the rail 11 may be completely removed from the tie.

15 A railroad tie constructed in accordance with the above will be of very simple and durable construction, and will be lighter in weight and cheaper to manufacture than solid metal ties, while presenting all of the durable qualities of the latter, by the provision of the metallic seat block 6 embedded therein. Also, the fastening means is simple, effective in action, and capable of being cheaply and easily manufactured as well as easily and expeditiously placed in use.

20 Minor changes may be made without de-

parting from the spirit and scope of the invention as claimed.

What I claim as new is:

1. A fastening device for a tie of molded composition material comprising a trapezoidal metallic block molded in said material and anchored against moving laterally of the tie and means for fastening the rail to said block. 30

2. A railroad tie comprising a body of molded composition material, a metallic block embedded in the upper portion of said body and being of substantially trapezoidal form in side elevation, said block having its upper shorter surface substantially flush with the upper surface of the body to form a rail seat, and having its sides flush with the sides of said body, means carried by said block for securing a rail on the upper surface thereof, the ends of said block being provided with central longitudinal ribs for preventing sidewise displacement of the block relative to the body. 40

45 In testimony whereof I affix my signature.

COLLIN THOMPSON.
